[57] **CLAIM**

The ornamental design for a portion of a bottom surface of a shoe outsole, as shown and described.

DESCRIPTION

FIG. 1 is a perspective view of a portion of a bottom surface of a shoe outsole showing my new design; and,

FIG. 2 is a bottom plan view of the portion of a bottom surface of a shoe outside shown in FIG. 1.

The broken line showing of the remainder of the shoe outsole is for illustration purposes only and forms no part of the claimed design.

1 Claim, 2 Drawing Sheets

FIG. 2
